UNITED STATES PATENT OFFICE

118,062

DESIGN FOR A TOY

Fred S. Welch and Glyn O. White, Los Angeles,
Calif., assignors to Clyde S. Payne, Junior,
Los Angeles, Calif.

Application May 18, 1939, Serial No. 85,076

Term of patent 7 years

To all whom it may concern:

Be it known that we, Fred S. Welch and Glyn O. White, citizens of the United States of America, residing at Los Angeles, county of Los Angeles, and State of California, have invented a new, original, and ornamental Design for a Toy, of which the following is a specification, reference being had to the accompanying drawing, forming part thereof.

Fig. 1 is a side view of the toy showing our new design.

Fig. 2 is a front view of the toy.

Fig. 3 is a rear view of the toy.

We claim:

The ornamental design for a toy, as shown.

GLYN O. WHITE.
FRED S. WELCH.
